UNITED STATES PATENT OFFICE.

KARL G. SOMMER, OF BATTLE CREEK, MICHIGAN, ASSIGNOR TO AMERICAN STEAM PUMP COMPANY, OF BATTLE CREEK, MICHIGAN, A CORPORATION OF MICHIGAN.

CENTRIFUGAL FLUID VACUUM PUMP.

Application filed August 10, 1922. Serial No. 580,846.

To all whom it may concern:

Be it known that I, KARL G. SOMMER, a citizen of the United States, residing at Battle Creek, in the county of Calhoun and 5 State of Michigan, have invented certain new and useful Improvements in Centrifugal Fluid Vacuum Pumps; and I hereby declare that the following is a full, clear, and exact description thereof, reference 10 being had to the accompanying drawings, which form part of this specification.

This invention is an improvement in so-called centrifugal vacuum pumps; and its objects are to provide a pump capable of 15 drawing in a large amount of air or producing a high suction without using or consuming a great deal of power; that is positive in action and will deliver large volumes of air without pulsation; that is absolutely reliable and whose efficiency may be maintained for an indefinite period; and which can be driven by a high speed electric motor; to provide a pump simple in construction, and efficient and economical in 20 operation.

In the accompanying drawings I have illustrated one form of pump embodying the invention and I will explain the same with reference thereto and summarize in the 30 claims the essentials of the invention and the novel features of construction and novel combinations of parts for all of which protection is desired.

In said drawings:

35 Fig. 1 is a longitudinal vertical section through the pump in the plane of the main shaft.

Fig. 2 is a transverse vertical section through such pump on the line 2—2, Fig. 1.

40 Fig. 3 is a longitudinal horizontal section of the pump in the plane of the main shaft.

Fig. 4 is an enlarged detail view of one of the port plates; and

45 Fig. 5 is a reduced inner face view of one of the heads.

As shown in the drawings the pump comprises a casing, valve plates thereon, a rotor or runner, and a shaft; the runner and shaft being the only moving parts.

50 As shown the casing comprises a body casting 1 provided with supporting leg members 1^b and having an interior volute chamber 1^a in which the runner of rotor 5 is mounted. In the sides of the said chamber 55 are circular openings eccentric to the cham-

ber, which openings are closed as hereinafter explained.

The casing is also provided at diametrically opposite sides of the chamber 1^a with an inlet passage 1^c and an outlet passage 1^d which respectively communicate with 60 passages in the heads 2 as hereinafter explained; said passages 1^c and 1^d are connected with inlet and outlet pipes P² and P³ as indicated in Fig. 2.

The chamber 1^a is volute, that is, it gradually increases in cross section from the inlet toward the outlet end thereof, and the shaft 4 is eccentrically located in the said chamber 1^a. 70

The cylindric openings in the sides of the body 1 are concentric with the shaft 4, said openings being closed by annular projections 2^a on the heads 2.

The heads 2 are preferably of cast metal 75 and are provided with inlet and outlet passages as hereinafter explained, and with axial bearings for the shaft 4 which extends horizontally through the casing and carries the rotor or runner 5, which is eccentrically 80 mounted in the chamber in the casing as hereinafter explained. The heads 2 are bolted or otherwise secured to opposite sides of the base 1 as shown, and the projections 2^a help to secure and support the heads on the casing, and when the heads 2 are in place the chamber 1^a is tightly closed except as to the ports hereinafter referred to. Each head 2 is provided with a central 85 hub portion 2^b in which the shaft 4 is journaled, and exterior to the journal bearing 2^b in each hub portion is a chamber 2^e in which a suitable packing 2^f is placed, and confined by a gland 2^g in the usual manner. 90

Each head 2 is provided with an inlet 95 passage 2^c and an oppositely extending outlet passage 2^d (Figs. 3 and 5); which passages respectively communicate at their outer ends with the passages 1^c and 1^d in the casing 1. The inner end of the passage 2^c is preferably bifurcated and extends partly around the shaft 4, (see Figs. 3 and 5), and is provided with a series of inlet ports 2ⁱ in its inner side which communicate with inlet ports 6ⁱ in the port plates 6 hereinafter referred to. The inner end of the outlet passage 2^d may be also bifurcated, and is provided with outlet ports 2° which communicate with outlet ports 6° in the port plates 6 hereinafter referred to. 100 105 110

- The inner face of each head 2 is adjacent the ports 2ⁱ and 2° is annularly recessed as shown at 2^r to receive a port plate 6 which surrounds the shaft 4 and is interposed between the bottom of the recess 2^r and the adjacent end of the hub of the rotor or runner 5, which is mounted upon the shaft 4 within the chamber 1^a and between the heads 2.
- 10 The rotor or runner 5 is fixedly secured to the shaft 4 so that it rotates therewith. Said runner is preferably made of bronze and has hub portions which enter the recess 2^r in the heads 2, and has parallel radially disposed disk-like side walls 5^a which lie close to the side walls of the chamber 1^a, and between walls 5^a are disposed a series of curved blades 5^b which extend from the hub of the runner to the periphery of the walls 5^a and divide the runner into a series of small radially disposed pockets 5^c, which are open only at the periphery of the runner. The inner ends of the pockets are preferably divided by an annular rib or circumferential enlargement 5^d on the hub of the disk intermediate walls 5^a; and the bifurcations of each pocket extend toward the opposite ends of the hub of the runner and adjacent the port plates 6, and at the inner end of each bifurcation of each pocket 5^c is a port 5^p which is adapted to register first with the inlet ports 6ⁱ in the adjacent port plate 6 and then with the outlet ports 6° in the said port plate. The port plates 6 are fitted between the outer ends of the hub of the runner 5 and the bottoms of the adjacent recesses 2^r in the heads 2. Each port plate 6 is provided with a series of inlet ports 6ⁱ (see Fig. 4) adapted to register with a like series of ports 2ⁱ in the head 2, and with a set of outlet ports 6° adapted to register with passage 2^b in the head 2. In the example shown there are six inlet ports 6ⁱ and two outlet ports 6° in each plate 6. The size and number of inlet and outlet ports could be varied according to the suction or pressure desired to be obtained in the pump and the size of the pump.
- 50 The port plates 6 are preferably rotatorily adjusted in any suitable manner and by any suitable means, to enable the ports 6ⁱ, 6° therein to be brought into more or less complete register with the ports 2^b, 2ⁱ in the heads 2; so as to regulate the effective area of said ports and thereby increase or decrease the volume of and pressure on the air handled by the pump. One simple mode of rotatorial adjustment is to provide the port plates with apertures 6^s for the engagement of the head of a screw whose body can be engaged with any one of a series of threaded apertures 2^s in the related head 2 to fasten the plate when it is adjusted rotatorily to the desired position. The port plates 6 serve as packing between the ends

of runner 3 and the heads 2 and to avoid leakage the plates 6 should fit as close as possible to the runner 5 and the heads 2. The port plates 6 are stationary but adjustable and they can be removed and suitable packing placed between them and the heads 2 to take up any wear, if such should develop.

In the top of the casing 1 is a small chamber 1^f (Fig. 2) which has a port 1^g opening into chamber 1^a directly above the runner 5 at the point where the periphery of the runner most closely approaches the peripheral wall of the chamber 1^a. This chamber 1^f is adapted for connection with a pipe P¹ by which water or fluid under pressure can be supplied to the chamber 1^a to keep the same properly water sealed. Passage 1^e is adapted for connection with a pipe P² (Fig. 2) through which air and water can be drawn into the chamber 1^a through the passages 2^c and ports 2ⁱ, 6ⁱ, 5^p; and the passage 1^d is adapted for connection with a pipe P³ through which air and water may be forcibly expelled from the chamber 1^a through ports 5^p, 6^o, 2^o, and passage 2^d.

It will be seen from the drawing that the rotor is located eccentrically in the chamber 1^a that this chamber is volute, gradually increasing in cross section clockwise around the rotor from the inlet end (adjacent ports 6ⁱ) of the chamber to the outlet end thereof (adjacent ports 6^o). The vanes of the rotor 5 are preferably curved in the direction in which the rotor rotates, as shown.

The only communication between the passages 2^c and 2^d in the heads 2 is through the ports 2ⁱ, 6ⁱ, 5^p, chamber 1^a and other ports 5^p, 6^o, 2^o. The pump is always sealed by having the rotor in the chamber 1^a filled with water under pressure from the pipe P¹ which connects with an independent fluid supply apart from that to which the pipes P¹ or P³ are connected. The rotor may be operated at high speed, up to 1800 r. p. m.

As the runner rotates it draws the air and water through the suction passages 1^e, 2^c and inlet ports 2ⁱ, 6ⁱ, and port 5^p into the chamber 1^e, and discharges air and water through the ports 5^p, outlet port 6^o, 2^o and discharge passages 2^d, 1^d, to pipe P³. The air and water enter through ports 2ⁱ, 6ⁱ and 5^p at low pressure and velocity into the runner pockets and the speed and pressure thereof is accelerated in the volute chamber 1^a by the action of the runner, and the air is forced inwardly in the pockets by the pressure and discharged through ports 5^p and outlet ports 6°, 2° into the passages 2^d, 1^d, to the pipe P³. As the water in the chamber 1^a is caused to follow the outer wall thereof by centrifugal force, the air in the water is forced out through the ports 6°, 2° and passages 2^d, 1^d to the discharge pipe P³.

The centrifugal force of the water cir-

- culated in the chamber 1^a by the runner 5 causes the drawing in of the air and also the expulsion of same and the suction or drawing effect is accomplished by the velocity of the water in the casing 1. The water is moved from the inlet to the outlet by the operation of the runner, centrifugal force causing the water to assume the shape of the peripheral wall of the chamber 1^a in passing therethrough and a large amount of air is handled. The double suction runner having ports on each side and rotating in the volute chamber 1^a and being water sealed will effectively draw in air through the inlet ports and discharge the same through the outlet ports, and as the air is drawn in at each side and discharged at each side the pump will handle a very large volume of air at a low vacuum.
- 20 The runner is hydraulically balanced and there is no end thrust, which is essential to the high efficiency.
- The pressure of the fluid supplied through the opening 1^g will help force the discharge 25 of air through ports 6°, 2°. The pump is thus water sealed, and air and water are drawn in at both sides of the runner and are discharged on both sides thereof.
- 25 Ports 5^p must be at the inner extremities of the runner pockets and as close to the hub as possible in order to prevent trapping of air, and to allow all compressed air to escape, and therefore ensure greater volumetric efficiency.
- 35 It is preferable to make the runner as shown and to use two port plates 6 making each side of the pump capable of handling air; thus easily and actually doubling the efficiency of the pump with less power applied.
- 40 The described arrangement of runner and port plates and heads with the correctly shaped volute chamber and pressure maintained therein as described makes an efficient vacuum pump.
- 45 The shaft 4 can be driven by or arranged for direct connection to, any prime mover such as an electric motor, steam motor, or gasoline motor.
- The pump is positive in action and ex-50 hausts a very large volume of air and delivers it free from pulsation. It is absolutely reliable and its efficiency will be maintained for an indefinite period as the runner and shaft are the only moving parts. The pump
- 55 will stand up indefinitely because of the few moving parts, and the torque required to operate such pump is very low, as it is only necessary to overcome the inertia of the runner and shaft which are the only moving parts.
- 60 It is necessary to keep the clearance between the runner and casing walls at the ports at the minimum for effective operation. In order to avoid leakage it is necessary to have the port plates 6 set as close to the runner as possible. The clearance between the port plates and runner can be made very close to suit the service required. These plates can be removed and packing placed behind same to take up any wear and bring 70 the pump up to its original efficiency. This assures that the centrifugal force or pressure in the volute 1 will have a continuous drawing or vacuum effect throughout the whole pump from suction inlet to delivery outlet 75 and the pump constructed as shown and described produces a continuous drawing or vacuum when in operation.
- What I claim is:
1. In a centrifugal fluid vacuum pump or compressor; a casing having a chamber; a shaft extending through said chamber eccentrically thereof; a runner mounted on said shaft within said chamber having radially disposed pockets, and a port at the side of each pocket; said casing having inlet and outlet ports at the side of said chamber adjacent the ports in the runner; with an adjustable port plate interposed between the ports of the runner and the ports in the casing and provided with ports adapted to register with the ports in the casing and runner, substantially as described. 80
  2. In a pump as set forth in claim 1, means independent of the main fluid inlet for introducing fluid under pressure into said chamber at the point where the periphery of the chamber most closely approaches the periphery of the runner, to make a fluid seal in said chamber between the runner and the casing at such point. 95
  3. In a centrifugal fluid vacuum pump or compressor; a casing having a chamber; a shaft extending through said chamber eccentrically thereof; a runner mounted on said shaft within said chamber having radially disposed pockets and ports at the inner end and opposite sides of each pocket, said ports extending parallel with the axis of the runner; said casing having inlet and outlet ports in its side walls extending parallel to the axis of the runner, and inlet passages connecting with certain of said ports at each side of the runner, and outlet passages connecting with other of said ports at each side of the runner; the ports in the runner being adapted to alternately register with the inlet and the outlet ports in the casing as the runner rotates. 100
  4. In a pump as set forth in claim 3, plates interposed between the ports of the runner and the ports in the casing and provided with ports adapted to register with the ports in the casing and runner, substantially as described. 115
  5. In a pump as set forth in claim 3, means independent of the main fluid inlet for introducing fluid under pressure into said chamber at the point where the periphery of the chamber most closely approaches 120

the periphery of the runner, to make a fluid seal in said chamber between the runner and casing at such point.

6. In a centrifugal fluid vacuum pump or compressor; a casing having a chamber; a shaft extending through said chamber eccentrically thereof; a runner mounted on said shaft within said chamber having radially disposed pockets opening at the periphery of the runner and ports at the inner end and opposite sides of each pocket, said ports extending parallel with the axis of the runner; said casing having inlet and outlet ports in each side wall of the said chamber extending parallel to the axis of the runner, and inlet passages connecting with certain of said ports at each side of the runner, and outlet passages connecting with other of said ports at each side of the runner; the ports in the runner being adapted to alternately register with the inlet and the outlet ports in the casing as the runner rotates.

7. In a pump as set forth in claim 6, plates interposed between the ports in the runner and the ports in the casing and provided with ports adapted to register with the ports in the casing and runner, substantially as described.

8. In a pump as set forth in claim 6, means independent of the main fluid inlet for introducing fluid under pressure into said chamber at the point where the periphery of the chamber most closely approaches the periphery of the runner, to make a fluid seal in said chamber between the runner and the casing at such point.

9. In a centrifugal vacuum pump; a casing having a chamber; a shaft extending through said chamber eccentric thereto; said casing having circular recesses at opposite sides concentric with the shaft, and inlet and outlet ports extending parallel with the axis of the shaft in the outer walls of said recesses; inlet passages in the sides of the casing communicating with the inlet ports, and outlet passages in the sides of the casing communicating with the outlet ports; a runner in said chamber mounted on said shaft and having hub portions extending into the said circular recesses and provided with a series of peripherally disposed pockets and with ports at opposite sides of the said pockets adapted to register with the inlet and outlet ports in the casing as the runner rotates, substantially as described.

10. In a pump as set forth in claim 9, plates interposed between the ported ends of the runner and the ports in the casing and provided with ports adapted to register with the ports in the casing and runner for the purpose specified.

11. In a pump as set forth in claim 9, means independent of the main fluid inlet for introducing fluid under pressure into

said chamber at the point where the periphery of the chamber most closely approaches the periphery of the runner, to make a fluid seal in said chamber between the runner and the casing at such point.

12. In a centrifugal fluid vacuum pump; a casing having a chamber and openings in the sides of said chamber; a shaft extending through said chamber eccentric thereto; heads attached to the sides of the said casing and closing the openings in the said chamber and having circular recesses in their inner faces at opposite sides of said chamber concentric with the shaft, and inlet and outlet ports in the outer walls of said recesses; said heads having inlet passages communicating with the inlet ports, and outlet passages communicating with the outlet ports; a runner in the chamber mounted on said shaft, said runner having hub portions entering the said circular recesses and provided with a series of peripherally disposed pockets, and with ports at opposite sides of the said pockets adapted to register with the inlet and outlet ports in the heads as the runner rotates.

13. In a pump as set forth in claim 12, plates interposed between the ported ends of the runner and the ports in the heads and provided with ports adapted to register with the ports in the runner and in the heads.

14. In a pump as set forth in claim 12, means independent of the main fluid inlet for introducing fluid under pressure into said chamber at the point where the periphery of the chamber most closely approaches the periphery of the runner, to make a fluid seal in said chamber between the runner and the casing at such point.

15. In a centrifugal fluid vacuum pump; a casing having a chamber, openings at opposite sides of said chamber and eccentric thereto and inlet and outlet passages at opposite sides of said chamber; heads attached to opposite sides of said casing and provided with inwardly projecting portions closing said openings in the chamber and provided with circular recesses in said portions eccentric to the chamber, exterior hub portions concentric with the said recesses, and inlet and outlet ports opening into said recesses adjacent said hub portions; said heads having inlet passages communicating with the inlet ports and with the inlet passage in the casing, and outlet passages communicating with the outlet ports and the outlet passage in the casing; a shaft journaled in said heads and extending through the said chamber eccentric thereto; a runner mounted on said shaft within said chamber and having hub portions projecting into the circular recesses in the heads, and provided with radially projecting blades forming an annular series of pockets, and ports

at the bottom of the pockets and on opposite sides thereof adapted to register with the inlet and outlet ports.

16. In a pump as set forth in claim 15, 5 means independent of the main fluid inlet for introducing fluid under pressure into said chamber at the point where the periphery of the chamber most closely approaches the periphery of the runner, to make a fluid 10 seal in said chamber between the runner and the casing at such point.

17. In a pump as set forth in claim 15, port plates interposed between the ports in

the runner and the ports in the casing and provided with ports adapted to register 15 with the ports in the casing and runner.

18. In a pump as set forth in claim 15, port plates interposed between the ports in the runner and the ports in the casing and provided with ports adapted to register 20 with the ports in the casing and runner, said port plates being rotatorily adjustable for the purpose specified.

In testimony that I claim the foregoing as my own, I affix my signature.

KARL G. SOMMER.
